UNITED STATES PATENT OFFICE.

WILLIAM G. MAYER, OF PITTSBURGH, PENNSYLVANIA.

TRUCK.

1,278,971.

Specification of Letters Patent. Patented Sept. 17, 1918.

Application filed March 22, 1918. Serial No. 224,068.

To all whom it may concern:

Be it known that I, WILLIAM G. MAYER, a citizen of the United States, and a resident of Pittsburgh, in the county of Allegheny and State of Pennsylvania, have invented a new and useful Improvement in Trucks; and I do hereby declare the following to be a full, clear, and exact description thereof.

10 This invention relates to vehicles, and more particularly to vehicles having dumping bodies, and has for its particular object the arrangement of a hand operated mechanism for dumping the body.

15 Another and important object is the arrangement of the dumping mechanism so that both a pulling and lifting operation occurs simultaneously, thereby facilitating the raising of the body.

20 A still further object is to provide an end gate that may be hinged at the top or bottom, as desired, and to provide automatic closing mechanism therefor when hinged at the top.

25 Various other objects, such as simplicity, durability, cheapness in manufacture, and the general improvement of the art, will be brought out in the following specification and illustrated in the accompanying drawing, in which:

Figure 1 is a side elevation of a motor truck having the invention applied thereto and showing the body in dumping position;

Fig. 2 is a front view of the body of a 35 truck showing the dumping mechanism;

Fig. 3 is a rear view of the endgate construction;

Fig. 4 is a detail side view of the rear portion of the body showing the endgate hinged at the top for dumping, in full lines, and showing the same in dotted lines in partly open position and hinged at the bottom:

Fig. 5 is a detail view of the hinge construction:

Fig. 6 is a diagram arrangement; and D the operative boom.

Referring more particularly to the drawings, A designates the chassis as a whole, which comprises a frame 2, wheels 3, cab 4, and engine casing 5.

A body portion B is pivotally mounted at 6 to the frame of the chassis and has a base 55 or under frame 7, sides 8 and front 9. The

rear edge of each side is bound by a permanently secured metallic strip 10 having a U-shaped slot 11 at each end and adapted to be closed by a pin 12.

The rear end of the body portion B is adapted to be closed by an endgate 13 which may be selectively hinged at the top or bottom as desired. Endgate 13 has reinforcing strips 14 thereon, which have their ends bent upon themselves forming cylindrical rod receiving portions 15. Rods 16 pass through and are secured in the portions 15 and are adapted to engage within the slots 11 in member 10 and to be held therein by pins 12. It will be understood that rods 16 are adapted to be locked in either the upper or lower slots 11 according to which way the end gate is to be opened since by locking the rod 16 in the slots 11 a hinge connection is completed. 75

A chain 17 is passed through the eyes 18 on the endgate and eyes 19 on the sides of the body B in the usual fashion to control the movement of the endgate when it is hinged at the lower side.

The body portion B being pivotally mounted on the chassis at 6, as before described, is adapted to be raised into dumping position by means of a suitably arranged cable mechanism which causes a lifting action on the forward portion of the body and a pulling action on the rear portion. 85

The raising mechanism comprises a main shaft 20 journaled in bracket bearings 21 and having a large gear 22 secured on its one end. A stub-shaft 23 is journaled in one bearing and carries a power gear 24, and has its free end squared, at 25, for the reception of a suitable operating crank 25^a. 90 95

A dog or stop ratchet 24' is mounted on the bearing bracket 21 adjacent the gear 22 and adapted to normally engage the same to prevent its reverse movement.

A boom 26 is pivotally mounted on the 100 bracket bearings at 27 and extends upwardly and has a suitable pulley or sheave wheel 28 mounted at its upper end.

A channel track portion 29 is secured on the front of the body portion B and is composed of two angle irons secured together and having their lower ends spaced apart, to form clearance for the double sheaves 31 journaled in bearing 32 on the forward end of the body. 110 105

The boom 26 is adapted to ride upon the track 29 due to its pivotal mounting and to be guided by the side flanges thereto.

A second set of double sheaves 33 are 5 journaled in bearing 34 secured on the underside of the rear end of the chassis in line with said first double sheaves, and a single sheave 35 is journaled in bearing 36 on the rear end of the underside of the body B.

- 10 A suitable drum 37 having its surface grooved as at 38 for the reception of a cable 39 is mounted on the main shaft 20 and has one end of said cable secured thereto. Cable 39 is trained upwardly from the drum 15 37 over sheave 28 down and under one side of the double sheave 31, back under one side of sheave 33, up and around sheave 35, thence back under the other side of sheave 33, and under the other side of sheave 31, 20 thence upwardly to the eye 40 secured in the boom 26, the end of the cable being secured to the eye 40.

Lever arms 41 and 41^a are pivotally connected by one end to lugs 42 and 42^a formed 25 on strips 14 of the endgate and extend below the lower edge of such endgate. Cables 43 and 43^a are secured to the free ends of the lever arms 41 and 41^a respectively and are brought together and secured as at 44 30 then lead as one single cable forward and are secured as at 45 to the cable 39 at a point on the return lap after such cable has passed around the sheave 35. The above combination of levers 41 and 41^a and cables 42 and 35 42^a are so arranged that when the body B is raised for dumping the tension of the cables will be released allowing the endgate to open, and when the said body is lowered the cables will be tensioned thereby closing such 40 gate.

The operation of the device, in detail, is as follows:—

The complete vehicle being assembled, and it being desired to dump a load from the body B, the crank member 25^a is placed in position on the squared end of the stub-shaft 23; the crank is then turned driving the pinion 24 and large gear 22 on shaft 20. Drum 37 is secured on shaft 20 and is consequently rotated when such shaft rotates. 45 As drum 37 is rotated cable 39 will be wound upon the same thereby causing a lifting action on the sheaves 31 due to such cable being drawn over the pulley or sheave 28 on the boom 26. Simultaneously with the lifting action on the sheaves 31 the cable 39 will pull on the sheave 35 which is secured at the rear end of the body portion B. By the combined lifting and pulling action of the 50 cables, the body B will be rocked on its pivot 6 so as to raise the front portion and placing the body in inclined position.

When used for dumping the endgate member 9 is hinged at its upper edge to allow 60 it to automatically swing outwardly at the

bottom to discharge the load from the body B when such body is raised in its inclined position. Cable members 43 and 43^a are secured to lever arms 41 and 41^a hingedly secured to the endgate member 9 and extend 70 forwardly and are engaged with the main operating cable 39 at a point on its return loop past the sheaves 33. When the body portion B is raised the return loop of the cable 39 moves rearwardly, thereby allowing the cables 43 and 43^a to move rearwardly, permitting the endgate 9 to open to discharge the load from the body portion, and as the body B is lowered the return loop 80 of the cable 39 will move forwardly and consequently cables 43 and 43^a will move forwardly thereby automatically closing the endgate 9 when the body portion B is lowered.

It will be understood that when body 85 portion B is to be used for dumping, the chain 17 will be either removed or hung very loosely so as not to interfere with the action of the endgate.

When it is desired to use the vehicle for ordinary hauling, such as express work, the endgate is hinged at the bottom by removing pins 12 and placing them in the lower end of strips 10 thereby holding the lower rod 16 in the sockets 11 and releasing the upper rod 16. When the endgate is hinged at the bottom its movement is controlled by the chain 17 as in the ordinary endgate construction, and such gate may be lowered and raised at will without in any manner 100 interfering with the lever arms 41 or cables 43-43^a due to the hinged connection of such levers, since when the gate is lowered such levers will drop away from the gate.

While I have shown and described one 105 specific form of my invention, it will be understood that I do not wish to be limited to such construction, but that various changes in details of construction and design may be made without departing from the 110 spirit of my invention as claimed.

What I claim is:

1. A vehicle of the class described comprising a wheeled chassis, a body portion pivotally mounted on said chassis, a drum, a single cable secured to said drum and said body portion, said cable being adapted to be wound upon said drum and combined to simultaneously exert a lifting action on the forward end and a downward pulling action 115 on the rear end of said body to dump the same.

2. A vehicle of the class described comprising a wheeled chassis, a body portion pivotally mounted on said chassis a boom 120 pivotally mounted on said chassis, a drum and operating mechanism, and a cable secured to said drum and trained about suitable sheaves on said boom and said body and chassis, said cable being adapted to 125

exert a lifting action on the forward end and a downward pulling action on the rear end of said body.

3. A vehicle of the class described comprising a wheeled chassis, a body portion pivotally mounted on said chassis, a boom pivotally mounted on said chassis adapted to ride on a channel truck formed on the forward end of said body portion, and means for simultaneously lifting the forward end and pulling down the rear end of said body portion, said means comprising a drum and gearing mounted on said chassis adapted to be operated by hand, a sheave mounted on said boom, a double sheave mounted on the underside of the forward end of said body, a second double sheave mounted on said chassis, a single sheave mounted on the rear end of said body portion, and a cable member having one end secured to said drum and being trained over said sheave on said boom, under said first named double sheave, under said second named double sheave, around said last named single sheave, returned under said double sheaves and secured to said boom adjacent its upper end.

4. A vehicle of the class described comprising a wheeled chassis, a body portion pivotally mounted on said chassis, an end gate hinged by its upper edge to said body portion, a boom pivotally mounted on said chassis, a drum and operating mechanism on said chassis, a cable secured to said drum and trained about suitable sheaves on said

boom and said body and chassis, said cable being adapted to exert a lifting action on the forward end and a downward pulling action on the rear end of said body portion, and means connected to said cable for automatically closing and locking said endgate when said body is lowered.

5. The combination with a vehicle of the class described having a pivoted body portion, and a cable mechanism for dumping said body, of an endgate pivoted at its upper edge to said body portion, levers hingedly mounted on said endgate, and a flexible connection between said levers and said cable whereby said endgate will be free to open when said body is in dumping position and automatically closed and locked when said body is lowered.

6. The combination with a vehicle body having reinforcing strips secured to the rear end of the sides and each of said strips having slotted ends, of an end gate member having reinforcing strips thereon, said strips terminating in looped ends, rods carried by said strips, said rods being adapted to be engaged in said slotted ends of said first named strips, and pins for locking said rods in either the upper or lower strips as desired.

In testimony whereof, I, the said WILLIAM G. MAYER, have hereunto set my hand.

WILLIAM G. MAYER.
